(57) **CLAIM**

The ornamental design for a lighting fixture, as shown and described.

DESCRIPTION

FIG. 1 is a perspective view of a lighting fixture showing the present design;

FIG. 2 is a front view of the design depicted in FIG. 1;

FIG. 3 is a right side view of the design depicted in FIG. 1; the left side is the mirror image of FIG. 3.

FIG. 4 is a back view of the design depicted in FIG. 1;

FIG. 5 is a top view of the design depicted in FIG. 1; and, FIG. 6 is a bottom view of the design depicted in FIG. 1.

Those portions of the present design which are presented in phantom illustrate the environment of the design only and form no part of the claimed design. Moreover, the shading presented in the accompanying drawings is provided merely to highlight the contour of the design and is not intended to be illustrative of texture or gloss.
